APPARATUS FOR HEATING VEGETABLE OILS

Joseph Stewart, Elmhurst, N. Y.

Application March 12, 1938, Serial No. 195,450
In Great Britain October 7, 1936

1 Claim. (Cl. 257—184)

This invention relates to improvements in apparatus for heating vegetable oils, the invention being particularly useful for heating edible vegetable oils (such as cocoanut oil, palm oil and cotton seed oil) in treating such oils for the purpose of deodorizing or of dehydrating such oils.

The primary objects of the invention are to make provisions for rapidly and efficiently heating the oil and simultaneously freeing the oil of water vapor and all volatile products released during the heating of the oil.

In the accompanying drawing:

Fig. 1 is a vertical sectional view showing an oil heating apparatus embodying the invention; Fig. 2 is a detail sectional view on the line 2—2 of Fig. 1; and

Figs. 3 and 4 are detail horizontal sectional views showing certain modifications of the heating apparatus illustrated in Figs. 1 and 2.

Referring to the construction illustrated in Figs. 1 and 2, 10 designates a casing or chamber having leading from its bottom an oil outlet 11, and having leading from its top a vapor outlet or exhaust 12 which is connected to a suitable condenser and a suitable vacuum pump (not shown) for withdrawal of vapors from casing 10 by suction and the condensation of the withdrawn vapors.

Within the casing 10 is a vertical series of horizontally disposed oil-heating pipes 13 the axes of all of which pipes lie in the same vertical plane. The pipes of the series are connected by return bends 14 for circulation of a heating medium through the series of pipes, the lowermost pipe extending at one end out of the casing through a suitable stuffing box 15 to a suitable source of supply of heating medium, and the uppermost pipe extending at one end out of the casing through a suitable stuffing box 16 to a suitable exhaust for the heating medium.

Within the casing 10 and above the series or bank of pipes 13 is an oil delivery trough 17 which extends longitudinally of the uppermost one of the pipes 13 and has formed in its bottom substantially throughout the length of the pipes 13 a narrow oil-discharge slot 18 located in the vertical plane of the axes of the pipes 13 and very close to the top of the uppermost one of the pipes 13 as shown. The two longitudinal edge walls of slot 18 may be serrated as shown at 19.

The discharge slot of trough 17 should be close enough to the top of the uppermost one of the pipes 13 to discharge onto said pipe a very thin

sheet or film of oil which will contact that pipe directly above the pipe axis and split, without spattering or spraying, into thinner films each of half the thickness of the film passing through the slot to said pipe, each of which thinner films will flow down a different side of the uppermost pipe to the bottom of said pipe. To effect a transfer of each said thinner film (or division or half of the film passing through the slot of the trough) from each pipe 13 to the one below without splashing or spattering, there is provided between each two immediately superposed ones of the bank of pipes 13 a vertical plate 20, the plates of the series of plates 20 all lying in the vertical plane of the slot 18 and the axes of the pipes 13. Oil dropping from the lowermost one of the pipes 13 will be discharged through oil outlet 11. The bank of pipes 13 may be heated internally by passing steam, hot water, or hot furnace gases, etc. therethrough.

Oil to be heated is delivered into the receptacle or trough 17 by an oil supply pipe 40 having discharge branches 41 which discharge into the trough at points spaced apart longitudinally of the trough.

In Figs. 3 and 4 modified constructions are shown which can be used to especial advantage when heating oils to very high temperatures.

Thus for each pipe 13 there may be substituted a horizontal pipe 21 (Fig. 3) welded at each end to the casing 10. Extending through pipe 21 is a smaller pipe 22 welded at one end to the casing and extending at its other end through a stuffing box 23 welded in one end of pipe 21. Suitable packing rings 24 are held in the stuffing box by a gland 25, threaded studs 26 and nuts 27, thus sealing one end of the annular space between pipes 21 and 22, said space being closed at the other end thereof by a sealing ring 39 welded to the two pipes. Pipe 22 is free to expand and contract longitudinally independently of pipe 21. Each pipe 22 in the modified construction is open at one end to a heating medium supply header 28 and at its other end to a heating medium discharge or outlet header 29. The stuffing box is preferably provided with a water-jacket space 30 having a water inlet 31 and a water outlet 32. The closed annular space between the pipes 21 and 22 is filled with a heat-conducting fluid such as distilled water, mineral oil, a mixture of diphenyloxide and diphenyl, or other heat-conducting liquid having a suitably low vapor pressure at high temperature.

In Fig. 4 is indicated a modified structure in which for each tube or pipe 13 of Figs. 1 and 2

a pipe 33 is to be substituted, each pipe 33 being welded at both ends to the casing 10. Ordinary electric heaters 34 of the immersion type are screwed into internally threaded bushings 35 welded in opposite ends of pipe 33, said heaters extending into a body of heat conducting fluid confined in pipe 33, said fluid being of the type described in connection with the modified structure shown in Fig. 3.

5 In modifying the structure of Figs. 1 and 2 in accordance with Fig. 3, plates 20 should be employed between pipes 21, and such plates should be employed between pipes 33, when as described in connection with Fig. 4, pipes 33 are substituted for pipes 13.

10 In the construction shown in Fig. 3, a filling pipe 36 for the heat-conducting liquid is horizontally arranged above and close to the oil heating pipe 21 and its two discharge ends are connected to opposite ends of the said pipe 21. A supply pipe 37 for the heat-conducting liquid leads to pipe 36 and a shut-off valve 38 is provided in the supply pipe. When the space between pipes 21 and 22 is filled with the heat-conducting liquid and valve 38 is shut off and heat passed through pipe 22, the liquid between pipes 21 and 22 will promote uniform internal heating of pipe 21 from end to end.

15 From the foregoing it will be observed that according to the invention a thin sheet or film of oil is discharged and fed downward from a body of oil past heating means in such manner that the descending thin sheet or film is first divided (without splashing or spattering or being broken into drops) into two still thinner films each of half the thickness of the thin discharged sheet or film, which two extremely thin divisions of the original thin sheet or film flow

downward without splashing or spattering or breaking up into drops, and are heated at their adjacent faces and, at the same time, are subjected at their outer or non-adjacent faces to suction or sub-atmospheric pressure to withdraw water vapors or steam and all volatile products liberated at their outer faces, the invention providing for substantially uniform heating of all parts of the treated oil and for free and immediate release from the oil of vapors and volatile products resulting from the application of heat to the descending extremely thin films of heated oil.

20 As is well known, the maximum temperatures to which the oil should be raised are dependent upon the purpose of treatment by heat and, of course, should not be so great as to burn or otherwise adversely affect the oil. For example, as is well known, the desirable oil temperature for dehydration of vegetable oils is approximately 180 degrees Fahrenheit, and the desirable temperature for deodorizing such oils is approximately 450 to 500 degrees Fahrenheit.

25 What I claim is:

2 An apparatus for heating vegetable oils comprising a chamber having at its upper end a suction outlet for volatile products and having at its lower end a discharge outlet, a vertical series or bank of horizontally disposed oil-heating tubes extending transversely of the chamber with the 3 tube axes in a vertical plane, an oil discharging trough having a discharge slot in its lower side, the wall on each side of said slot being serrated to cause the oil to flow in an even film to the top side of the uppermost tube of the bank, 3 said heating tubes adapted to contain a heating fluid.

JOSEPH STEWART.
